MULTIPLE COIN ACTUATED VENDING
MACHINE

William L. Gilchrist, Los Angeles, Calif., and William T. Hoofnagle, Glen Ridge, N. J., assignors to Rowe Slug Ejector Co., Ltd., Los Angeles, Calif., a corporation of Nevada

Application June 24, 1932. Serial No. 619,028

9 Claims. (CL. 194—39)

This invention relates to improvements in multiple coin actuated vending machines.

The general object of the invention is to provide an improved coin released mechanism wherein a plurality of coins are required to operate the device.

Another object of the invention is to provide an improved coin released mechanism wherein various combinations of coins of different denominations will operate the device.

A further object of the invention is to provide a device of the class described including means whereby should an operator after depositing coins in the device and before actuating the coin released mechanism desire to have the coins returned he may operate the device to return the deposited coins.

A still further object of the invention is to provide a device of the class described including means to return to an operator a predetermined amount of change upon actuation of the coin release mechanism.

Other objects and the advantages of this invention will be apparent from the following description taken in connection with the accompanying drawings wherein:

Fig. 1 is a fragmentary sectional view of a vending machine showing our improved coin released mechanism operatively installed therein with portions of the coin released mechanism broken away.

Fig. 2 is a view similar to Fig. 1 showing the opposite side of the coin released mechanism.

Fig. 3 is a rear view of the device shown in Fig. 1.

Fig. 4 is a fragmentary view of the coin released mechanism showing the side thereof shown in Fig. 1 with the cover plate removed and showing a coin actuating a portion of the mechanism and

Fig. 5 is a similar view showing the coin actuating a different portion of the mechanism.

Referring to the drawings by reference characters, we have indicated our improved coin released mechanism generally at 10 and have shown it as operatively mounted in a vending machine housing 12. As shown the device 10 is adapted upon insertion of the proper coins, to release a plunger bar 14 which extends through the front of the housing 12 and is supported in brackets 15. The plunger bar 14 may act directly to discharge an article from the vending machine or it may act to release other plungers which when actuated discharge articles from the vending machine.

As shown the device 10 is adapted to actuate to release the plunger 14 by the insertion thereinto of dimes and nickels but it will be understood that it is adapted to any combination of sets of two coins.

The device 10 comprises a body portion 16 which is shown as adapted to be secured to portions of the vending machine housing by bolts 17. One side of the body 16 such as indicated by D and shown in Fig. 1 will be designated as the dime side of the device and the opposite side such as shown in Fig. 2 and indicated by N will be designated as the nickel side of the device.

On the dime side of the body 16, we provide an entrance raceway 18 which is formed by a rear abutment portion 19 and a front abutment portion 20 both of which are integral with the body 16. Spaced a predetermined distance below the lower ends of the abutments 19 and 20, we provide an abutment portion 21 which is inclined forwardly and downwardly and is adapted to direct coins towards a rearwardly curved portion 22 of an abutment portion 23. The forward end of the abutment portion 21 is spaced a predetermined distance from the rear face of the abutment portion 23. Spaced below the curved portion 22 of the abutment 23, we provide an aperture 24 in the body 16 through which coins are adapted to be directed to the nickel side of the body by a downwardly inclined portion 25 which is integral with the body 16.

Positioned on the abutments 19, 20, 21 and 23, we provide a cover plate 26 which is secured to the body by a plurality of screws 27 and extends from the top of the body downward to adjacent the top of the aperture 24.

On the nickel side of the body we provide an entrance raceway 28 which is formed by a forwardly and downwardly inclined abutment portion 29. The raceway 28 is adapted to direct coins towards a rearwardly curved section 30 of an abutment portion 31 and the lower end of the abutment portion 29 is spaced a predetermined distance from the rear face of the abutment portion 31. The lower end of the curved section 30 is spaced a predetermined distance above the aperture 24 and coins leaving the curved section 30 are directed rearwardly and downwardly towards abutment portions 32 and 33 which in turn direct the coins into the chute 25.

Positioned on the abutments 29, 31, 32 and 33, we provide a cover plate 34 which is secured to the body by a plurality of screws 35 and extends from the top of the body downward to adjacent the top of the aperture 24. As shown dimes are

directed from the exterior of the vending machine housing 12 to the dime entrance raceway 18 of the device 10 by a suitable coin chute 36 and nickels are directed from the exterior of 5 the vending machine housing to the nickel entrance raceway 28 by a suitable coin chute 37.

Pivottally mounted on the body 16 as at 38 on the dime side thereof, we provide a lever 39 which in the front of its pivot includes a portion 40 10 which projects into the entrance raceway 18 a predetermined distance and in the rear includes a working face 41.

Pivottally mounted on the body 16 as at 42 below the abutment portion 21, we provide a lever 15 43 which at the rear of its pivot includes a working face 44. At the front of its pivot the lever 43 curves downwardly and then curves forwardly and terminates in a forwardly projecting portion 45 the end of which is normally spaced a predetermined distance below the end of the curved 20 section 22 of the abutment 23 and above the top of the aperture 24. Intermediate the length of the lever 43, we provide a pin 46 which projects through an arcuately shaped elongated aperture 25 47 in the body 16 to the nickel side of the body at a point a predetermined distance below and to the rear of the end of the curved section 30 of the abutment portion 31 (see Fig. 2).

To prevent rearward movement of the plunger bar 14, we provide a dog 48 which is pivotally secured to the body 16 as at 49. The dog 48 includes an abutment face 50 which is adapted to be engaged by a vertical face 51 of a notch 52 provided in the upper face of the plunger bar 14. The bottom of the notch 52 is inclined upwardly towards the rear to allow free forward movement of the plunger bar. The dog 48 further includes an upwardly projecting portion 53 having thereon a rearwardly projecting finger member 54.

For swinging the dog 48 upward about its pivot, we provide a lever 55 which is pivotally mounted adjacent one end on a bolt 56 which is secured to the body 16. The opposite end of the lever 55 45 terminates in a partially rounded portion 57 which is positioned directly below the finger 54 on the dog 48.

For actuating the lever 55, we provide another lever 58 which is also pivotally mounted on the bolt 56. The lever 58 extends rearwardly at a downward inclination a predetermined distance and forwardly of the pivot bolt 56 the lever includes an enlarged portion or head 59 which includes a plurality of substantially vertically spaced apertures 60. Adapted to be positioned in one of the apertures 60, we provide a pin 61 which is also adapted to be positioned in a correspondingly sized aperture provided in the lever 55. Thus when the rear of the lever 58 is moved 55 downwardly the pin 61 will move upwardly and move the end 57 of the lever 55 upward which in turn will engage the finger 54 of the dog 48 and swing the free end of the dog upward out of the notch 52 in the plunger bar 14 whereupon the plunger bar is free to be moved rearwardly.

For moving the rear of the lever 58 downward, we provide a vertically movable bar 63 which is slidably mounted in bearings 64 which are integral with the body 16 and extend outwardly from the face thereof on the nickel side.

Adjacent the lower end the bar 63 includes a reduced portion 65 to which we secure a bolt 66 having a roller 67 rotatably mounted thereon (see Fig. 3). Extending along most of the length

of the bar 63, we provide gear teeth 68 on the forward face thereof.

Intermediate the bearings 64, we provide a gear 69 which meshes with the gear teeth 68 on the bar 63. The gear 69 is secured to a shaft 70 which is rotatably supported in the body 16 and extends therethrough to the dime side where an escapement wheel 71 is secured thereto. The escapement wheel 71 includes a plurality of evenly spaced radially extending ratchet teeth 72.

Positioned between the face of the body 16 and the adjacent face of the escapement wheel 71, we provide a plate 73 which is supported by bolts 74 positioned in elongated apertures 75 provided in the plate 73. To normally prevent rotation of the escapement wheel 71 in an anticlockwise direction we provide a finger 76 on the plate 73 which is normally engaged by one of the ratchet teeth 72. To normally retain the finger 76 in engagement with one of the ratchet teeth 72 of the escapement wheel we provide a horse shoe spring 77 one end of which is anchored to a port 78 on the body 16 and the other end of which engages a finger 79 provided on the plate 73 and resiliently urges the plate 73 forwardly.

To prevent rotation of the escapement wheel 71 more than the distance between the ratchet teeth 72 when the finger 76 is moved out of engagement with a ratchet tooth we provide a finger 80 on the plate 73. Normally the finger 80 is 105 out of engagement with the escapement wheel as shown in Fig. 1. The finger 79 of the plate 73 is engaged by the working face 41 of the pivoted lever 39 and the working face 44 of the pivoted lever 43 engages a finger 81 provided on 110 the plate 73.

With the pin 61 of the lever 58 positioned in the lowermost aperture 60 the device is adapted to be actuated to release the plunger bar 14 by the insertion into the device 10 of twenty-five cents in 115 change. That is it may be actuated to release the plunger bar by the insertion into the device 10 of two dimes and a nickel, one dime and three nickels or five nickels.

When an operator inserts a dime in the dime 120 coin chute 36 it is directed to the dime inlet raceway 18 of the device 10. As the dime moves downward in the raceway 18 it engages the end portion 40 of the lever 39 and the weight of the dime swings the end 40 of the lever downwardly until the dime engages the abutment member 21 whereupon the dime rolls out of engagement with the lever 39 (see Fig. 4).

As the end 40 of the lever 39 is thus moved downward the lower corner of the working face 130 41 of the lever moves rearwardly and moves the plate 73 rearwardly against the action of the spring 77. As the plate 73 moves rearwardly the finger 76 thereof moves out of engagement with the escapement whereupon the weight of the bar 135 63 moves the bar downward thereby rotating the gear 69 and the escapement wheel 71. The finger 80 on the plate 73 is so spaced from the finger 76 that it allows one ratchet tooth to pass thereby before it moves into engagement with the 140 escapement and as the escapement rotates prevents the next ratchet tooth from passing thereby stopping the downward travel of the bar 63. When the dime moves out of engagement with the lever 39 the spring 77 returns the plate 73 to 145 its initial position wherein the finger 80 is out of engagement with the escapement wheel and the finger 76 is in engagement with the escapement wheel.

As the dime leaves the abutment 21 it is di. 150

rected towards the curved section 22 of the abutment 23 which in turn directs it downwardly and rearwardly into engagement with the lower end portion 45 of the lever 43. When the dime 5 engages the lever 43 the weight of the dime moves the portion 45 of the lever downward to the position shown in Fig. 5 whereupon the dime rolls out of engagement with the lever 43 and into the chute 25.

10 When the portion 45 of the lever 43 moves downward the lower corner of the working face 44 of the lever moves rearwardly and moves the plate 73 rearwardly against the action of the spring 77 whereupon the weight of the bar 63 15 rotates the escapement the distance between teeth as previously described. From the foregoing it will be apparent that a single dime passing through the device 10 actuates the mechanism thereof to allow the bar 63 to move downwardly 20 two steps. Thus two dimes will actuate the mechanism to allow the bar 63 to move downwardly four steps.

When the operator inserts a nickel in the nickel chute 37 it is directed to the nickel inlet race-way 28 which in turn directs it into engagement with the curved section 30 of the abutment portion 31. As the nickel leaves the curved section 30 it engages the pin 46 of the lever 43 whereupon the weight of the nickel swings the portion 45 30 of the lever 43 downward to a predetermined point and then rolls out of engagement with the pin 46 whereupon it is directed into the coin chute 25 by the abutment portion 33. As the nickel swings the portion 45 of the lever 43 downward the lever actuates the plate 73 in the same manner as previously described in connection with the dime operation to allow the bar 63 to move downward one step. Thus it will be seen that each nickel 40 passing through the device 10 actuates the mechanism thereof to allow the bar 63 to move downwardly one step.

From the foregoing it will be apparent that when two dimes and one nickel have passed through the device 10 the bar 63 has moved downwardly five steps.

As the bar 63 is moving downward on its fifth step the roller 67 thereon engages the end of the lever 58 and moves it downward thereby moving the dog 48 out of the notch 52 of the plunger bar 14 whereupon the plunger bar is free to be moved rearwardly by the operator as previously described.

When the coins enter the coin chute 25 they are directed thereby into a coin hopper 82 which is pivotally mounted on a bolt 83 secured to a lug 84 which is integral with the coin chute 25. When the coins reach the lower end of the hopper 82 they come to rest on a shelf 85 which is secured to the housing 12 and positioned adjacent the lower end of the hopper.

When the operator moves the plunger bar 14 rearwardly a roller 86 rotatably mounted thereon engages the hopper 82 and swings the lower end thereof rearwardly as shown in Fig. 2 in which position the lower end of the hopper aligns with a coin chute 87 which directs the coins to a suitable coin receiver.

To reset the bar 63 to its initial position, we provide a lever 88 which is pivotally mounted on the body 16 as at 89. Adjacent the pivot 89 the lever includes an enlarged portion 90 having a forward working face 91 and a lower cam face 92.

When the bar 63 is in a lowered position as indicated by the broken lines in Fig. 2 and the operator moves the plunger bar 14 rearwardly a

roller 93 rotatably mounted thereon engages the face 91 of the lever 88 and swings the lever about its pivot 89 thereby moving the rear of the lever upward which in turn engages the roller 67 on the bar 63 and moves the bar 63 upward to its initial position as shown in Fig. 2.

After depositing the required amount of coins to operate the device 10 or a portion of the required amount, the operator wishes to have the deposited coins returned he may do so by pulling the plunger bar 14 forwardly. As the plunger bar moves forwardly a roller 94 rotatably mounted thereon swings the lower end of the coin hopper 82 forwardly into alignment with a coin return chute 95 which directs the coins through an aperture 96 in the front of the housing 12 and into a coin return receptacle 97 (see the broken line position in Fig. 1).

At the same time the roller 94 engages the hopper 82 it engages the cam face 92 of the lever 88 and moves it upward thereby moving the rear of the lever 88 upward which in turn engages the roller 67 on the bar 63 and moves the bar 63 upward to its initial position.

For returning a predetermined amount of change upon each complete operation of the device, we provide a change return mechanism which is indicated generally at 100. As shown the device 100 includes a base 101 which is secured to the device 10 by a plurality of the cover bolts 27 on the dime side. The base 101 has a groove 102 therein which is approximately the same depth as the thickness of a one cent coin and in which we position a slide bar 103. Adjacent the forward end of the base 101, we provide a coin hopper 104 which is mounted on shim bars 105 positioned on each side of the groove 102. If but one cent in change is to be returned the shim bars 105 are omitted and when more than one cent is to be returned the thickness of the shim bars correspond in height to the combined thickness of the number of coins to be returned above one.

Extending rearwardly from the coin hopper 105 we provide spaced overhanging portions 106 which retain the slide bar 103 in the groove 102. The coin hopper 104 includes a vertical aperture 107 in which one cent pieces 109 are positioned flatwise. The lowest cent in the device 100 rests on the upper face of the base 101.

When more than one cent is to be returned, we provide a shim 110 adjacent the forward end of the slide bar which corresponds in thickness to the combined thickness of the coins above one to be returned.

Extending downwardly from the slide bar 103, we provide an arm 112 which has a roller 113 pivotally mounted thereon adjacent the lower end thereof.

Pivotally mounted on the body 16 as at 114, we provide a lever 115. The lever 115 includes an arm 116 which extends upwardly from the pivot 114 and a finger 117 which extends downwardly from the pivot 114.

When the plunger bar 14 is moved rearwardly a projection 118 thereon engages the finger 117 of the lever 115 and moves it rearwardly thus swinging the arm 116 of the lever forwardly (see Fig. 2). As the lever 115 is thus moved the arm 116 engages the rolls 113 on the arm 112 of the slide bar 103 and moves the slide bar 103 forwardly. As the slide bar 103 is thus moved the two lowermost one cent pieces 109 are moved forwardly and out of the device 100. When the coins leave the

device 100 they fall into a coin chute 120 which directs them into the return coin chute 95.

When the plunger 14 is released a spring 121, which is secured to the coin chute 36 by a boss 122 and to the shim 110 by a boss 123, causes the plunger to assume its original position.

From the foregoing description it will be apparent that we have provided the novel coin released device which is simple in construction and highly efficient in use.

Having thus described our invention, we claim:

1. In a coin device, a plunger, a pivoted dog adapted to engage said plunger and normally prevent movement thereof in one direction, a lever 15 pivoted adjacent one end, the opposite end of said lever engaging a portion of said dog to move it out of engagement with said plunger bar, a second lever pivoted intermediate its length, means adjacent one end of said second lever engaging said first lever to move the latter, a release bar slidably mounted and movable into engagement with said second lever, gear teeth on said release bar, a gear, said gear meshing with said bar gear teeth, a rotatably mounted shaft, said gear being secured to said shaft, an escapement wheel secured to said shaft, said escapement wheel including a plurality of spaced ratchet teeth, a movable plate adjacent said escapement wheel, a finger on said plate, a second finger on said plate, resilient means engaging said plate and normally swinging said first finger into engagement with said escapement wheel to prevent rotation of said escapement wheel, said second finger when said first finger engages said escapement wheel being out of engagement with said escapement wheel, means whereby a plurality of coins of different denominations actuate said plate to free said escapement wheel whereby said bar moves toward said second lever, said 20 second finger when said first finger moves out of engagement with said escapement wheel being adapted to move into engagement with said escapement wheel to prevent rotation thereof beyond a predetermined amount, means whereby 25 coins of different denominations free said escapement wheel a predetermined number of different times, said bar being adapted to engage said second lever and move said second lever whereupon said second lever moves said first lever and said 30 first lever moves said dog out of engagement with said plunger and means whereby when said plunger is moved in one direction said bar will be returned to its initial position.

2. In a coin device, a plunger, means engaging said plunger to normally prevent movement thereof in one direction, means to release the first means, said last mentioned means including a step by step device, a plurality of coin chutes, a pivoted lever adjacent the exit of each of said coin chutes, means whereby one of said levers when rocked advances said step by step device one step, means whereby the other lever when rocked also advances the step by step device one step and means whereby a coin after striking the first lever and operating the bar one step advances and strikes the second lever, whereby the same coin actuates the step by step device another step, whereby when a sufficient number of coins have been disposed the device will move to free 35 said plunger for movement in one direction.

3. In a coin device, a plunger, holding means to engage said plunger and normally prevent movement thereof in one direction, releasing means engaging a portion of said holding means to move 40 the latter out of engagement with said plunger,

means to operate said releasing means, said last means including a release bar, means to give said release bar a step by step movement, said last mentioned means including a ratchet device co-acting with said bar, a plurality of coin chutes, a pivoted lever adjacent the exit of each of said coin chutes, means whereby one of said levers when rocked advances said bar one step, means whereby the other lever when rocked also advances the bar one step and means whereby a coin after striking the first lever and operating the bar one step advances and strikes the second lever, whereby the same coin actuates the bar another step.

4. In a coin device, a plunger, a pivoted dog adapted to engage said plunger and normally prevent movement thereof in one direction, a lever engaging a portion of said dog to move it out of engagement with said plunger, means to move said first lever, a release bar slidably mounted and movable into engagement with lever moving means, gear teeth on said release bar, a gear, said gear meshing with said bar gear teeth, a rotatably mounted shaft, said gear being secured to said shaft, an escapement wheel secured to said shaft, means to normally prevent movement of said escapement wheel, and means whereby a plurality of coins of different denominations free said escapement wheel whereby said bar moves said lever moving means to thereby move said lever, whereupon said lever moves said dog out of engagement with said plunger.

5. In a coin device, a sliding plunger, a pivoted dog engaging said plunger to normally prevent movement thereof in one direction, a lever engaging said dog to move it out of engagement with said plunger, a second lever having means engaging said first lever to move the latter, a release bar slidably mounted and movable into engagement with said second lever, means to give said release bar a step by step movement, said last mentioned means including a ratchet device co-acting with said bar, a plurality of coin chutes, a pivoted lever adjacent each of said coin chutes, means whereby one of said levers when rocked advances said bar one step, means whereby the other lever when rocked also advances the bar one step and means whereby a coin after striking the first lever and operating the bar one step advances and strikes the second lever, whereby the same coin actuates the bar another step.

6. In a coin device, a plunger, a pivoted dog adapted to engage said plunger and normally prevent movement thereof in one direction, a lever pivoted adjacent one end, the opposite end of said lever engaging a portion of said dog to move it out of engagement with said plunger, a second lever pivoted intermediate its length, means on said second lever engaging said first lever to move the latter, a release bar movably into engagement with said second lever, means including an escapement device to normally hold said release bar against movement, means whereby a coin actuates said escapement device to free said bar whereby said bar moves toward said second lever, said bar being adapted to engage said second lever and move said second lever whereupon said second lever moves said first lever and said first lever moves said dog out of engagement with said plunger.

7. In a coin device, a plunger, a pivoted dog adapted to engage said plunger and normally prevent movement thereof in one direction, a lever pivoted adjacent one end, the opposite end of said lever engaging a portion of said dog to move it out

- of engagement with said plunger, a second lever pivoted intermediate its length, adjustable means on said second lever engaging said first lever to move the latter, a release bar slidably mounted 5 and movable into engagement with said second lever, means including an escapement device to normally hold said release bar against movement, means whereby a plurality of coins of different denominations actuate said escapement device to 10 free said bar whereby said bar moves towards said second lever, means whereby coins of different denominations free said escapement device a predetermined number of different times, said bar being adapted to engage said second lever 15 and move said second lever whereupon said second lever moves said first lever and said first lever moves said dog out of engagement with said plunger and means whereby when said plunger is moved in one direction said bar will be returned 20 to its initial position.
8. In a coin device, a plunger, a dog adapted to engage said plunger and normally prevent movement thereof in one direction, a pivoted lever having a portion engaging said dog to move it out 25 of engagement with said plunger, a second lever, means on said second lever engaging said first lever to move the latter, a release bar movable into engagement with said second lever, gear teeth on said release bar, a gear, said gear meshing with said bar gear teeth, a shaft, said gear being secured to said shaft, an escapement wheel secured to said shaft, said escapement 30 wheel including a plurality of spaced ratchet teeth, a movable plate adjacent said escapement wheel, a finger on said plate, a second finger on said plate, means engaging said plate and normally swinging said first finger into engagement with said escapement wheel to prevent rotation of said escapement wheel, said second finger when said first finger engages said escapement wheel being out of engagement with said escapement wheel, means whereby said plate 35 frees said escapement wheel whereby said bar moves toward said second lever, said second finger when said first finger moves out of engagement with said escapement wheel being adapted to move into engagement with said escapement wheel to prevent rotation thereof beyond a predetermined amount and means whereby coins of different denominations free said escapement wheel a predetermined number of different times, said bar being adapted to engage said second lever and move said second lever whereupon said second lever moves said first lever and said first lever moves said dog out of engagement with 40 said plunger.
